FIG. 1.

FIG. 2.

FIG. 3.

Inventor
F. J. Jackson

By Marks Clark
Atty's

UNITED STATES PATENT OFFICE.

FREDERICK JAMES JACKSON, OF AUCKLAND, NEW ZEALAND.

ANCHOR.

Application filed June 16, 1922. Serial No. 563,808.

To all whom it may concern:

Be it known that I, FREDERICK JAMES JACKSON, citizen of the Dominion of New Zealand, residing at Mahurangi Heads,

5 Auckland, in the Provincial District of Auckland, New Zealand, have invented certain new and useful Improvements in Anchors, of which the following is a specification.

10 This invention relates to anchors used for mooring vessels and has for its object the provision of an anchor the flukes of which will engage in or obtain a grip of the sea bed, no matter how the anchor is thrown overboard. A further object is to make the anchor collapsible for the purpose of facilitating its handling and stowage.

According to the invention the anchor is provided with a head slideable on the shank, 20 and from which project flukes curved towards the end of the shank to which the chain or line is attached, and equally spaced around said head.

A stop on the outer or lower end of the 25 shank prevents the head from leaving the shank at said end, while at the other end of the shank it is enabled to pass on to the attached chain or line, so that it may lie more or less flat with the shank.

30 In the accompanying drawing, in conjunction with which the invention will be further described:—

Figure 1 is a perspective view of the anchor in the position it assumes prior to the 35 flukes engaging in the sea bed.

Figure 2 is a vertical section of the anchor and.

Figure 3 shows same collapsed, for stowing on deck or out of the way.

40 In the drawing 1 is the shank which is provided at its outer end with a stop 2, for the purpose of preventing the head from leaving the shank at that end.

At its other end the shank is provided 45 with an eye 4 to which is attached an elongated link 5 having connected thereto a ring 6 to serve as a stop.

The head 3 is slideable on the shank 1 and link 5, between the ring or stop 6 thereon and the stop 2 at the opposite end of the 50 shank.

The flukes 7 are formed integral with the head 3 and curve towards the eye end 4 of the shank.

Any desired number of flukes 7 can be 55 provided, the latter being equally spaced around the head 3.

To facilitate the stowing away of the anchor, the head 3 is slid off the shank 1 on to the link 5, until it makes contact with the 60 ring or stop 6. The anchor can then be laid on deck or stowed away, with the head 3 and flukes 7 lying approximately flat with the shank 1.

When thrown overboard the pull of the 65 chain or line 8 causes the shank 1 to occupy a position with the eye 4 uppermost whereupon the head 3 slides down the shank against the stop 2, so that the lowermost of the flukes 7 are ready for entering or engag- 70 ing in the sea bed.

By providing the flukes 7 equally spaced around the head 3, some of the flukes are always ready to enter or engage in the sea bed.

What I do claim and desire to obtain by 75 Letters Patent of the United States of America is:—

An anchor comprising a shank formed with a stop at one end and acting when the anchor is in operative position and an eye 80 at the other end; an elongated link attached to said eye and a ring connected to said link and serving as a stop when the anchor is folded; a head provided with flukes, slideable on the shank and said link between the first 85 mentioned stop and the ring and a flexible element attached to said ring.

In testimony whereof I have affixed my signature in presence of two witnesses.

FREDERICK JAMES JACKSON.

Witnesses:

WILLIAM PINCHES,
MARY PUKINGTON.
